J. Edmonds
ATTORNEY

UNITED STATES PATENT OFFICE.

GEORGE A. PECK, OF NEW ROCHELLE, NEW YORK.

INTERCHANGEABLE GLOVE.

Application filed October 18, 1924. Serial No. 744,305.

To all whom it may concern:

Be it known that I, GEORGE A. PECK, a citizen of the United States, and resident of New Rochelle, in the county of West-
5 chester and State of New York, have invented certain new and useful Improvements in Interchangeable Gloves, of which the following is a specification.

This invention relates to interchangeable gloves, and more particularly relates to 10 gloves made of rubber or similar material designed for use by surgeons. It is essential that gloves used by surgeons when practicing upon patients must be sterile, and also 15 that they do not interfere with the surgeon's ability to feel through the glove. Such articles are very easily contaminated by handling or touching foreign substances. When a surgeon has a supply of sterilized 20 gloves, some of which are suited only for the right hand and the others only for the left hand, it very often happens that he picks up and attempts to put on his hand 25 a glove which is suited only to his other hand. Such handling of the glove often contaminates it and prevents it from being used until it has been sterilized again. To avoid this objectionable feature, it has been 30 proposed to provide a rubber glove which is reversible, so that it may be placed on either hand. The design of such gloves, however, has been such that the glove forms 35 wrinkles across the palm of the hand, and seriously interferes with the surgeon's ability to feel through the glove. For this reason these gloves are very objectionable.

The principal aim of my invention is to overcome the above objectionable features, and to provide a rubber glove particularly 40 suitable for use by surgeons, and which may be used indiscriminately on either hand, and a glove which, at the same time, presents a flat unwrinkled surface over the palm of whichever hand the glove is placed, and 45 does not interfere with the wearer's ability to feel through the glove.

Another object of my invention is to provide a glove of the character described which is simple and inexpensive in construction and one which may be put on or taken 50 off readily and easily.

Other objects of my invention will be in part obvious and in part pointed out hereinafter.

55 In accordance with my invention, the

glove is constructed of very elastic material, and the thumb portion is placed centrally with respect to the palm portion, so that, when a hand is inserted into the glove, the thumb may be placed in the 60 thumb portion and then, by moving the thumb to its normal position with respect to the hand, the thumb portion of the glove may be moved and rotated toward one side or the other of the glove, depending upon 65 which hand, either right or left, is inserted into the glove. The movement of this thumb portion in this manner stretches the material of the glove flat across the palm of the hand without causing any wrinkles to 70 form on the palm.

In order that a clearer understanding of my invention may be had, attention is hereby directed to the accompanying drawings, forming a part of this application and illustrating one possible embodiment of my invention.

Referring to the drawings:

Fig. 1 is a front view of a glove embodying my invention, looking toward the palm 80 side;

Fig. 2 is a side view of the glove;

Fig. 3 is a front view of a portion of the glove, showing its normal position on a hand; and

Fig. 4 is a sectional view of the glove as worn, and is taken on the line 4-4 of Fig. 3.

Referring to the drawings, the glove comprises an integral piece of thin rubber formed to shape, as by molding. However, the glove may be formed of several pieces suitably vulcanized or otherwise secured together. As shown, the glove comprises a tubular portion, the lower end of which, 1, is the wrist portion. Above the wrist portion is a palm portion 2, back portion 3, and side portions 4. Upwardly of the palm and back portions extend four tubular finger portions, the two end ones 5 being of equal height and each being long enough to accommodate the first finger of either of the wearer's hands. The two middle fingers 6 are also of equal height and each is long enough to accommodate the second finger of each of the wearer's hands. A thumb portion 7 has an enlarged base 8 extending outwardly from the lower central portion of the palm 2. Portion 8 is open into the interior of the glove. A portion 9 extends upwardly from the portion 8, and is tubular,

and of such shape and size as to snugly accommodate the thumb of either of the wearer's hands.

In Fig. 3, the glove is shown placed on a wearer's left hand. In placing the glove on either hand, the thumb of the wearer is rotated inwardly towards the palm of the hand, and then the hand is slid into the glove, so that the four fingers of the wearer 5 enters the four finger portions of the glove and the wearer's thumb enters the thumb portion 9. The wearer may then rotate his thumb toward the thumb side of his hand. This will bring the thumb portion of the 10 glove to the side of the glove, (as shown in Fig. 3, when the left hand is used), and will stretch the palm portion 2 of the glove 15 tightly across the palm 10 of the wearer's hand 11, as shown in Fig. 4. When the 20 glove is placed on the right hand, the thumb portion will be drawn to the right of the glove, and when the glove is placed on the left hand, the thumb portion will be drawn to the left of the glove, and in each case the 25 palm portion 2 will be stretched in un-wrinkled condition across the wearer's palm, thus providing a flat surface through which the surgeon may feel.

As many changes could be made in the 30 above construction and as many apparently

widely different embodiments of this invention could be made without departing from the scope thereof, it is intended that all matter contained in the above description or shown in the accompanying drawings be 35 interpreted as illustrative and not in a limiting sense.

What I claim is:—

1. A surgeon's glove made of elastic material and including a back portion, a palm portion, finger stalls above the palm portion, and a thumb portion joining the palm portion midway between the side edges thereof, the elasticity of the material of the glove permitting the thumb portion to be 40 moved to either side of the palm, and the glove being adapted to either hand of the wearer without reversal. 45

2. A surgeon's glove made of highly elastic material and including finger stalls and a thumb stall arranged below and centrally with respect to the finger stalls, whereby the glove may be placed on either hand of a wearer and the entire thumb stall drawn to either side of the glove accompanied by 50 stretching of the material across the palm of the wearer's hand. 55

This specification signed this 11 day of October, 1924.

GEORGE A. PECK.
